UNITED STATES PATENT OFFICE.

JOHN K. KNIGHT, OF NEW YORK, N. Y., ASSIGNOR TO WILLIAM H. BAKER.

RAILWAY BLOCK SIGNAL.

SPECIFICATION forming part of Letters Patent No. 291,860, dated January 1, 1884.

Application filed July 24, 1882. (No model.)

To all whom it may concern:

Be it known that I, JOHN K. KNIGHT, a citizen of the United States, and a resident of New York, in the county of New York and State of New York, have invented certain new and useful Improvements in Railway Block Signals, of which the following is a specification.

The object of my invention is, first, to simplify and improve the construction of electro-magnetically controlled locking devices employed in electric signal, draw-bridge, or switch apparatus for railways; and to this end my invention consists in the combination, with the lever, operating-rod, or other portion of the operating mechanism for the semaphore disk or indicator, or for the switch or bridge lock, of a catch provided with a suitable retracting-spring or other device exerting a constant force, which tends to withdraw it from engagement with the operating mechanism, and an electro-magnet the armature of which is arranged to engage with the catch and prevent its withdrawal until such electro-magnet is energized or de-energized, as the case may be, so as to withdraw the armature or allow it to be withdrawn out of range of the catch, and thus allow the retracting device of the catch to act.

My invention further consists in the combination, with the operating mechanism for the signal, switch, bridge-lock, or other device, of a device connected to and moving with such mechanism, and arranged to engage with the catch and throw it into position, where it will lock said operating mechanism and will itself be detained by the armature of the electro-magnet.

My invention further relates to block signals wherein the line of a railway is divided into sections, at each end of which are suitable signals for indicating to an approaching train the condition of the next ensuing section; and the object of my invention is to provide a simple and effective combination of devices whereby it shall be impossible for the operator at one station to give the signal of "line clear" to a train approaching a station without the concurrence of the operator at the distant end of the section which the train is approaching. A further object is to so ar-

range the apparatus that the operators may communicate with one another over the same wire by which their signals are unlocked.

My invention consists in a novel combination of hand-operated semaphores provided with automatic locking devices, electro-magnets for releasing the same, switches controlling electric batteries, and signaling keys and bells arranged at the stations of a block signal system for railways in the manner hereinafter set forth, so that the operation of the system for a double-track road may take place over a single line-wire connecting the stations.

My invention further consists in the novel combination of a hand-operated semaphore at one station, biased so as to stand normally at "danger," a lock for holding it in "danger" position, an electro-magnet for releasing said lock, and two switches or keys controlling the circuit of said electro-magnet—one at the home station with said electro-magnet and the other at the next station in advance.

My invention consists, further, in certain specific combinations of apparatus that will be detailed in the claims.

In the accompanying drawings, Figure 1 is an elevation of my improved locking devices. Fig. 2 is a detail view. Fig. 3 is a diagram showing my improved block signal system and the application thereto of the improved locking devices shown in Fig. 1.

Referring to Fig. 1, B indicates the connecting-rod by which the semaphore-signal, the railroad-switch, or the draw-bridge lock is operated, and B' a collar or projection thereupon, with which a locking-catch, A, may engage, said catch A consisting, by preference, of a pivoted lever, as shown, provided with a retracting-spring, D, which constantly tends to disengage it from the rod B, so as to allow the latter to be operated.

C indicates an electro-magnet, the circuit of which is controlled by any of the means or in any of the ways known to the art for the purpose of releasing the signal or switch operating mechanism. The armature C' of this electro-magnet is provided with the usual retracting-spring, and is here shown as arranged to drop into the path of the catch A, so as to prevent its disengagement, so long as the electro-magnet C is not energized. When the armature

is attracted, however, it is carried out of range of the catch A, and the retractor D thereupon withdraws the catch A, carrying it back beneath the armature C and against a stop, C', thus freeing the rod B or other operating mechanism, so that the latter may be operated, either by hand or otherwise, to set or unset the signal, operate the switch, or lock or unlock the draw-bridge.

10 It is obvious that the electro-magnet C and its armature might be so arranged as to lock the catch when the armature is energized and to unlock it when the armature falls away.

In order that the catch A may be restored 15 to a locking position beneath the collar B', and where the armature may drop down behind and lock it, an arm, B'', attached to the rod B, is provided, which arm carries a laterally-projecting pin, B'', Fig. 2, arranged to 20 pass behind an inclined spring, A'', or other suitable projection upon the catch A, when the rod B returns to its normal position, so as to force the catch in toward the rod and beneath the projection B'.

25 D' indicates an electrical contact-spring, which bears against the collar B' when the signal-operating mechanism is in a locked position, and thus completes a break in the circuit of a circuit-closer, or of an electro-magnet 30 used for locking or unlocking another signaling or switch-operating mechanism for operating a semaphore or other signal, or for any of the usual purposes of electric railway signaling. One of the special uses of such 35 contact-spring will be described in connection with Fig. 3.

In the special application of the locking devices to be presently described, the rod B is connected with a biased semaphore-arm, 40 biased to show "danger" when the rod is in the position shown in the drawings and locked. When the magnet C is energized, the catch A is retracted by its spring, and the rod B may be moved in the direction of the arrow by a 45 connection with a suitable manually-operated lever until the semaphore is thrown to "safety," the arm B'' and its operating-pin being in this operation carried below the spring A'', so that when the semaphore is released 50 and the rod B is carried back the pin passes behind the spring, and the locking parts are thus restored to their first position.

It is obviously within the scope of the invention to apply the lock to other moving portions of the signal, switch, or bridge-lock operating devices, and to also vary the form and disposition of the movable catch A.

My lock possesses the merit of simplicity, and is also valuable because the armature can 60 not be subjected to any strain from the switch or signal-operating mechanism, its duty being confined to preventing the movement of the catch under the stress of a suitably-adjusted retracting spring, weight, or other device acting with a constant and determinate force sufficient only to withdraw the catch.

In Fig. 3 is illustrated the application of

my invention to a block system for a double-track road, two of the stations of the block system being shown. For convenience, we 70 shall call the track upon which trains move in the direction of the arrow 1 the "uptrack" and that upon which trains move in the direction of the arrow 2 the "downtrack."

E and F are the two stations at opposite ends 75 of a section of the line of road, each of which is provided with means for operating a semaphore for the uptrack and a semaphore for the downtrack, the uptrack-semaphore at F and the downtrack-semaphore at E guarding the 80 section of track between the stations.

The semaphores consist of the ordinary biased arm, arranged to swing across the track and indicate "danger," and to be drawn down to indicate "safety" by means of hand-operated 85 levers a a, connected through rods B with the semaphores, a suitable counterbalance or biasing weight being provided, which will tend to hold the semaphores normally at "danger," and will immediately restore them to "danger" 90 when the operating-lever is released after having been used to move them to "safety" to give the signal of "line clear" to an approaching train.

M M indicate casings containing the mechanism for controlling the semaphores for the uptrack, and N N those for the downtrack semaphores. Signal-bells b b and signaling-keys k k are used at each station for communicating with the adjoining stations, those on 100 the left of each station being used for signaling to the station to the left and those on the right for signaling to the station to the right. The two bell electro-magnets at each station are polarized oppositely from the releasing electro-magnets C C, which, in the present arrangement, are also polarized, and are connected to the back contact-stops of the signaling-keys k, the front contact-stops of which latter are connected with section M B' of a main 110 battery, so that when the key is depressed the bell is cut off and the battery M B' placed to the line, either to the right or to the left of the station, according to which key is operated. The section M B of battery at each station is 115 used to release the locking devices, so as to allow a semaphore to be set to "safety," as will presently more clearly appear.

Referring to the up-signal apparatus, M K' indicates a push-button or battery-key controlling a switch-spring, which, in its normal position, closes the circuit from the line leading from station at the rear to the signaling-key k at the left of the station, and when operated by the push-buttons cuts off the key 120 and through spring D', bearing upon the semaphore-connecting rod B, connects the section M B of battery to line with a polarity the opposite of M B', so that if the releasing-key k' at the rear station be simultaneously operated 125 the releasing-magnet C at the latter will be energized, and the semaphore may be set to "safety." Push-button or key k' at each station serves the purpose of connecting the line 130

leading to the station ahead directly to the releasing-magnet, so that if the battery-key k^2 at that station be operated at the same time the semaphore mechanism is released. When 5 the spring for push-button k' is at rest, it completes the circuit between the line to the station ahead and the bell and key b k , used for signaling to station to the left. The apparatus N for the downtrack is provided with 10 similar push-buttons or keys d' and d^2 , one of which, d' , serves to close the circuit to the releasing-magnet at its station, while the other, d^2 , serves to connect the battery M B to line, so that if the key d^2 at the station to the left 15 or in the rear be simultaneously operated the semaphore mechanism at the latter will be released.

The circuits and connections are as follows, the parts all being at rest and occupying the 20 normal position shown, with the semaphores at "danger." At station F the line-circuit connecting E and F is through the spring of the releasing key or switch k' for the up-line semaphore, a contact-stop against which said spring normally rests, the spring of battery-key or push-button d^2 in the down-line semaphore apparatus N, a contact-stop against which said spring normally rests, and thence to the key k for signaling to the left, back stop 25 therefor, and polarized bell b . At station E the line-circuit is through the releasing-switch or key d' for down-line semaphore, and its normal contact-stop, thence through a connecting-wire to the spring of the battery key or 30 switch k^2 for the up-line semaphore, its normal contact-stop, key k for signaling to the right, back contact-stop therefor, and corresponding polarized bell, b . At E the line from station to the left passes through the releasing 35 switch or key for the uptrack, in the same manner that the connecting-line 15 passes to earth at F, while at F the line-section leading to the right passes to earth at F through the releasing switch or key for the downtrack-semaphore and the battery-switch for the uptrack-semaphore, in the same manner that connecting-line 15 passes to earth at E.

Let it be supposed that the operator at F desires to set the uptrack-semaphore to "safety" 40 to allow the passage of a train onto the section of track between E and F. To enable him to do this, the magnet C of M at station F must be energized, and for this purpose both the unsetting or releasing switch k' at his own 45 station and the battery-switch k^2 at the next station E in advance must be simultaneously operated. By operating key k at the left of F and key k at the right of E, the two operators may communicate with one another; but 50 the operator at F cannot unset his signal until the operator at E allows him to do so by actuating battery-switch k^2 , and cannot even then do so unless operator at E has reset his signal to "danger," so as to protect any train that 55 may have passed onto the section beyond, for the reason that while the signal at E is unset, or at "safety" the circuit from the battery M B

at E is broken at the spring D' . The currents sent by the operator at E in the act of signaling to F by his key k cannot act to unlock 70 the semaphore at F, although the operator at F might simultaneously actuate his unsetting switch or key k' , because the magnet C is polarized to respond only to currents coming from battery M B, which latter is controlled by the 75 battery-switch k^2 . The bell-magnet b at F, being oppositely polarized, will, however, respond to the currents from M B sent by the 80 signaling-key k at E, as will also the bell-magnet b at E to the battery M B at F, being polarized and properly connected for that 85 purpose. The same operation takes place when operator at E desires to signal "line clear" to an approaching train on the down-track. Normally the downtrack-semaphore 90 at E is at "danger," and is locked by the catch A, controlled by magnet C. The catch can only release the semaphore when the magnet C is energized, and this can only be brought about by the concurrence of the two operators, the operator at F depressing his battery-key d^2 at the same time that operator at E depresses his releasing-key d' , so as to connect the magnet C to the section 15 of line. In this operation, as before, operator at F can 95 not connect battery M B to line unless he shall have first restored his semaphore mechanism to its normal position, so as to close the circuit at spring D' of N, in which position the section of line to the right of F is blocked 100 to trains on the downtrack, and remains blocked until the operator at station to right of F allows the semaphore apparatus N at F to be released.

By the above arrangement, not only can the 105 line 15 between two stations be used for the purpose of communication by keys and bells or sounders, but it also serves as the connecting-wire for controlling the semaphore-operating mechanism at the two stations. Not 110 only can these operations be performed without danger of derangement or false action, but by reason of the peculiar arrangement and connection of the devices the same line serves 115 for controlling the semaphores of both the up and down tracks.

I do not limit myself to the construction or arrangement of keys and batteries, whereby currents of opposite polarity may be caused to circulate for the purposes described. There 120 are other and well-known arrangements and devices for this purpose that may be employed.

In actual construction I propose to place the electro magnet C in a local circuit controlled by a polarized relay connected in the same portion of the general circuits as the electro-magnet C in Fig. 3. Such an arrangement is indicated in Fig. 4, R being the polarized relay, and the other parts being indicated by the same letters as previously used.

While I have shown my invention as employed in a system in which a normally-open circuit is used, it will be understood that the same might be employed with a normally-

closed circuit, the connections being suitably made for that purpose and the relation of the parts reversed. As this is a matter within the province of those well versed in the art, I have not deemed it necessary to describe the same in detail.

While I have shown in my block system, Fig. 3, a peculiar locking appliance, I do not wish to be understood as limiting myself thereto, since the locking device is but one element of such system, and the general character of the invention there shown would remain the same, although other mechanical devices might be employed for locking the mechanism by which the semaphore is thrown and held at "safety."

In Fig. 5 I have shown a device applied to the locking mechanism for the signal or other apparatus for showing to the operator the condition of such signal—that is, whether set to "danger" or "safety," or whether locked or unlocked. The device consists of an indicator attached or connected to the armature of the locking and unlocking electro-magnet, so as to move with it, and to occupy one position when the armature is in position for locking the operating mechanism and to occupy another position when said mechanism is unlocked. I prefer to use for this purpose a card moving behind an opening in the casing, which encloses the locking mechanism, although it is obvious that a pointer might be used in its place. A card bearing the words "Locked" and "Unlocked," or "Blocked" and "Clear," is shown at 50, attached by an arm or support, 40, directly to the locking-armature, and arranged to move up and down behind an opening, 45, in the box containing the locking mechanism.

When the armature is retracted, and the operating mechanism therefore locked, the word "Locked" appears at the opening 45, the word "Unlocked" being hidden. When the armature is attracted, and the operating mechanism therefore unlocked, the word "Unlocked" upon the card is brought up into line with the opening.

What I claim as my invention is—

1. The combination, with the operating-rod for a railroad-signal, switch, or draw-bridge lock, of a pivoted locking-catch engaging with said rod, a retractor tending to withdraw said catch, and a detaining-armature engaging directly with the catch.

2. The combination, with a reciprocating operating-rod for a signal, switch, or draw-bridge, of a locking-catch provided with a retractor and normally locking said rod from movement in one direction, a detaining-armature arranged, when operated, to release the catch, and means upon said reciprocating rod for engaging with said catch upon a movement of the rod in the opposite direction, and moving said catch into normal locking position with relation to the rod.

3. The combination, with a connecting-rod, B, for a signal or switch mechanism, of a col-

lar or shoulder, B', a pivoted catch for engaging with the same, a retractor constantly tending to disengage the catch, and an armature, 70 C, detaining the catch.

4. The combination of the connecting-rod B, having collar or shoulder B', of a pivoted catch, A, and its retractor, a spring, A", mounted upon the catch, and a pin or projection carried by the rod for engaging with the spring A" and restoring the catch to a locking position.

5. The combination of rod and collar B B', swinging catch A and its retractor, detaining-armature C, and mechanism upon the rod for engaging with the catch and restoring it to a locking position.

6. The combination of a semaphore biased to indicate "danger," mechanism for withdrawing the same against its biasing device, so as to cause it to indicate "safety," a lock or catch for locking said mechanism against such movement, an electro-magnet controlling the catch, two keys or switches in the same circuit with 90 said electro-magnet, one at the home station and the other at the next station in advance, and at the latter station a circuit-closer in said controlled circuit, operated by the semaphore mechanism at said station, and arranged to 95 be closed only when said semaphore is at "danger."

7. The combination, in a block signal apparatus, of a series of stations connected by a single line, semaphore mechanism at each 100 station, an electro-magnet for controlling the same, polarized to respond to a current of one kind or polarity, a signal-bell or other receiving apparatus arranged to respond to currents of an opposite polarity or kind, and two manual signaling-keys and battery at each station, for sending currents of the proper polarity to operate the semaphore-magnet or the signal-bell at the next station.

8. The combination, in a block signal apparatus, of a biased semaphore normally indicating "danger," mechanism for operating the same to cause it to show "safety," a catch for engaging with said mechanism, a retractor applied to the catch for causing its disengagement, a restraining electro-magnet, a switch for connecting said electro-magnet with the line running to the station in the rear, and at the latter station a key or switch and a battery, whereby the detaining electro-magnet at 120 the station in advance may be operated only when both keys are actuated together.

9. The combination, in a block signaling system, of a biased semaphore normally indicating "danger," an electro magnet and locking 125 device for controlling the position of the same, said magnet being constructed to respond to currents of one kind or polarity, a signal-bell at the same station constructed to respond to a current of the opposite kind or polarity, and 130 two keys, one at the same station with the semaphore-magnet and the other at the next station in advance, with circuit-connections, as described, whereby the closing of both keys

is necessary in order to complete the circuit of and energize the semaphore-magnet.

10. The combination, with two semaphore mechanisms at the same station, one for the up and the other for the down track, of a releasing-key, k' , for one mechanism, and a battery key, d' , connected in the circuit to one side of the station, a corresponding releasing-key, d' , and battery-key connected in the circuit to the other side of the station, said battery-keys being suitably connected to batteries, so as to send a current of one kind or polarity, and signaling-keys—one in each circuit—connected so as to send a current of the

15 opposite kind or polarity.

11. The combination of the biased semaphore, the operating-rod B, the circuit-closer D', battery M B, the key controlling the common circuit of D'', and the battery-connections from the key to the station in the rear, and a 20 releasing electro-magnet, C, at the latter station.

Signed at New York, in the county of New York and State of New York, this 22d day of July, A. D. 1882.
